UNITED STATES PATENT OFFICE.

MITCHELL E. RYTHON AND FRANK E. HILLERY, OF COMANCHE, OKLAHOMA.

ROOST.

1,249,202.

Specification of Letters Patent. Patented Dec. 4, 1917.

Application filed May 7, 1917. Serial No. 166,972.

To all whom it may concern:

Be it known that we, MITCHELL E. RYTHON and FRANK E. HILLERY, citizens of the United States, residing at Comanche, in the county of Stephens and State of Oklahoma, have invented certain new and useful Improvements in Roosts, of which the following is a specification, reference being had to the accompanying drawings.

10 This invention relates to certain improvements in roosts for chickens or other fowl, and it is an object of the invention to provide a novel and improved device of this general character including perches adapted 15 to receive a vermin exterminating fluid, and wherein said perches are provided with openings through which the fumes of the fluid are adapted to pass.

It is also an object of the invention to provide a device of this general character including a novel and improved perch which is formed from a single strip of material and which is provided with means whereby the same may be conveniently and effectively maintained in applied position.

The invention consists in the details of construction and in the combination and arrangement of the several parts of our improved roost whereby certain important advantages are attained and the device is rendered simpler, less expensive and otherwise more convenient and advantageous for use, all as will be hereinafter more fully set forth.

35 The novel features of the invention will hereinafter be definitely claimed.

In order that our invention may be the better understood, we will now proceed to describe the same with reference to the accompanying drawings; wherein—

Figure 1 is a longitudinal, vertical sectional view taken through a roost constructed in accordance with an embodiment of our invention;

45 Fig. 2 is a view taken substantially on the line 2—2 of Fig. 1; and

Fig. 3 is an enlarged fragmentary view in perspective of an end portion of a perch as herein disclosed.

50 As herein embodied my improved roost comprises the parallel angle irons 1, supported upon a predetermined incline by the legs 2, also of angle iron and which have their upper extremities operatively connected with the depending side flanges of the irons 1. The irons or side members 1

are maintained in predetermined spaced relation through the medium of the perches P.

As herein embodied each of the perches P is formed from a single strip of material 60 rolled transversely to afford a substantially cylindrical body, with the marginal edges thereof disposed upwardly and substantially in contact. The opposite end portions of the cylindrical perch are flattened, as indicated at 5, and said flattened portions are extended upwardly in substantially the form of an inverted L. The foot 2 of each of the flattened portions 5 is adapted to overlie the upper flange of an iron or side 70 member 1, and anchored thereto through the medium of a removable bolt 3, or the like. Adjacent margins of the rolled strip in close proximity to a flattened portion of the iron 1 are provided with registering recesses 4, affording a filling opening whereby the exterminating fluid may be readily poured within a container afforded by the intermediate tubular or cylindrical portion of the perch P. At opposite sides of the 75 margins of the strip and in predetermined longitudinally spaced relation are openings 6, extending between the flattened end portions 5 of the perch and through which are adapted to escape the fumes of the liquid 80 or fluid within the perch. It will be at once self-evident that the particular position of the openings 6 results in the escape of the fumes to substantially contact with the fowl roosting on the perch so that the 85 vermin on said fowl will be destroyed.

It is also preferred that the meeting edges or margins of a perch which are adjacent and inwardly of the flattened portions 5, be sealed, as indicated at 7, by solder or the 90 like, so that the fluid or liquid may be readily retained within the hollow or intermediate portion of the perch P.

From the foregoing description, it is thought to be obvious that a roost constructed in accordance with our invention is of an extremely simple and comparatively inexpensive nature and is particularly well adapted for use by reason of the convenience and facility with which it may be assembled, and it will also be obvious that our invention is susceptible of some change and modification without material departure from the principles and spirit thereof and for this reason we do not wish to be understood as limiting ourselves to the precise arrangement and formation of the several 105 110

parts herein shown in carrying out our invention in practice, except as hereinafter claimed.

We claim:

5. 1. A roost comprising spaced side members and perches interposed therebetween, each of said perches having its intermediate portion tubular and its opposite end portions flattened, each of said flattened portions being substantially in the form of an inverted L with its outer portion overlying an adjacent side member, and means for securing said outer portion to the side member, the upper face of the tubular portion 10 of the perch being provided with openings.
2. A roost comprising spaced side members and perches interposed therebetween, each of said perches having its intermediate portion tubular and its opposite end portions flattened, each of said flattened portions being substantially in the form of an inverted L with its outer portion overlying an adjacent side member, and means for securing said outer portion to the side member, the upper face of the tubular portion 15 of the perch being provided with openings, said openings being arranged in transversely spaced series, the openings of each series ex-

tending longitudinally of the tubular portion of the perch.

3. A roost comprising spaced side members and perches interposed therebetween, each of said perches having its intermediate portion tubular and its opposite end portions flattened, each of said flattened portions being substantially in the form of an inverted L with its outer portion overlying an adjacent side member, and means for securing said outer portion to the side member, the upper face of the tubular portion of the perch being provided with openings, said openings being arranged in transversely spaced series, the openings of each series extending longitudinally of the tubular portion of the perch, said tubular portion of the perch adjacent an end thereof and intermediate the series of openings being provided with a filling opening.

In testimony whereof we hereunto affix our signatures in the presence of two witnesses.

MITCHELL E. RYTHE.
FRANK E. HILLERY.
